UNITED STATES PATENT OFFICE.

FREDERICK HOYER MILLENER, OF OMAHA, NEBRASKA.

TRANSMITTER FOR ETHERIC OR WIRELESS TELEPHONE SYSTEMS.

1,200,210.

Specification of Letters Patent.

Patented Oct. 3, 1916.

Application filed November 7, 1912. Serial No. 730,923.

To all whom it may concern:

Be it known that I, FREDERICK H. MILLENER, a citizen of the United States, residing at Omaha, in the county of Douglas and 5 State of Nebraska, have invented certain new and useful Improvements in Transmitters for Etheric or Wireless Telephone Systems, of which the following is a specification.

10 This invention has reference to a transmitter for use in an ethereal or wireless telephone system, and is designed more particularly for use in connection with apparatus set forth in my pending applications, Serial No. 620,035, filed April 10, 1911, and Serial No. 624,118, filed April 19, 1911, though it may be used in other telephonic systems. The purpose sought is to impress upon the transmitting medium or ethereal 15 waves, sharp, clear, and adequate impulses, insuring correspondingly sharp, clear, and powerful reproduction at the receiving station. To this end the apparatus is constructed as shown in the accompanying 20 drawings, representing a typical embodiment of the invention, wherein:

Figure 1 is a perspective elevation showing both the transmitting and receiving apparatus mounted upon a common board or 25 support, the transmitter being on the right-hand half; Fig. 2 is a section on the line 2—2 of Fig. 1; Fig. 3 is a detail view of the microphone button, supporting bridge, etc., within the transmitter; and Fig. 4 is a dia- 30 grammatic illustration of the electrical connections.

In these drawings 1 indicates a board or support, upon which are mounted the transmitting apparatus A and the receiving 40 apparatus B, with such other special devices as may be deemed convenient or necessary. To the board or support 1 is secured an insulating slab or plate 2, to which are applied insulating binding posts 3, 4, 5 and 6. 45 7 indicates the usual bracket-arm or support, such as is commonly employed for the ordinary Bell telephone transmitter, and 8 the arm hinged or pivoted to said bracket, and serving to support the transmitter. 50 Formed with, or secured to the free or outer end of said arm 8 by screws or other suitable fastenings, is a head or block 9, conveniently made of circular form, and having a series of holes or openings 10 equally spaced 55 about its axis, and extending obliquely to said axis through the block or head from

one face to the other, as well illustrated in Fig. 2. These several openings are all at common angle to the axis of the block or head 9, and to the axis of the megaphone 60 horn 11 and mouthpiece 12 carried thereby. Each of the holes or openings 10 in the head or block 9 is enlarged to receive one end of a tube 13, the opposite end of which carries a shell or casing 14 having the usual telephonic transmitter, preferably of the type or construction set forth in Letters Patent No. 485,311 to A. C. White, dated November 1, 1892. This specific construction is not essential to the present invention, and 65 is merely noted as illustrating one of many forms of microphonic transmitter suitable for use in this connection. The tubes 13 may be soldered, screwed, or otherwise made fast in the head 9, and should be as nearly 70 alike as possible in all dimensions—length, diameter, thickness, and also in kind and quality of metal, alloy or material. They should be equally spaced, and bear like relation to the megaphone 11 and its mouthpiece 75 12, and their interior surfaces should form continuations of the openings 10 through the head 9 without shoulder or break, and the inner surfaces of the tubes 13 and openings 10 as also of the megaphone, should 80 be very smooth or highly polished.

The shells 14 each comprise an annular base 15, screwed or otherwise secured to the tubes 13, and a dome-shaped cap or cover 16. Within the chamber inclosed by said base 90 and cap is arranged the diaphragm 17, with which the microphone button 18 is mechanically connected, said button being carried as usual by a bridge-piece 19 in electrical contact with the base 15, and through the latter with the tubes 13, head 9, supporting arm 8 and bracket 7. An insulating thimble or socket-piece 20 passing through the cap 16, and supported upon the bridge-piece 19, carries and insulates a conducting thimble 21, which receives the end or terminal of a conducting wire 22. The thimble 21 is in turn electrically connected with the microphone button 18, or the movable member thereof, by a wire or conductor 23, as shown 95 in Fig. 3. In other words, the construction and arrangement of parts in the shell or casing 14 are as usual in transmitters of the type indicated.

From the binding screw 4 a conducting 110 wire 24 passes to and is electrically connected with the supporting bracket 7 of the arm

8. Mounted upon a shelf or support below the bracket 7 and upon the insulating slab or plate 2, is a group or series of open-core transformers 25, one for each transmitter head 14, and from each of said transmitter heads 14 a wire 22 connected as above described, passes to and connects with the primary coil of one or another of said open-core transformers. All of said primary coils or windings are of like ohmic resistance, having the same number of turns of wire of the same kind, quality and cross section. The secondary coils or windings of the transformers 25 are similarly of like ohmic resistance, and of wire of the same kind, quality and cross section, and of like number of turns.

Referring to Fig. 4, it will be seen that the primary coils or windings 26, 27, 28, 29, 30 and 31 of the transformers 25 are connected in parallel between the conductors 32' and 32" of a local battery 32, or other source of electric energy, each primary including in the bridge between said conductors one of the low-resistance, air-cooled transmitters above described, contained within the several shells or casings 14.

33, 34, 35, 36, 37 and 38 indicate the secondary coils of the transformers 25, which 30 secondaries are arranged in parallel between the conductors 39 and 40, through which the transmitting apparatus is connected with the wave-generating apparatus of the system. A condenser 41, of advisably two microfarad capacity or thereabout, is introduced into the line or conductor 39, and a like condenser 42 is introduced into the conductor 40, as indicated.

As the present invention pertains solely 40 to the transmitting apparatus above described, it is deemed unnecessary to show or describe more of the ethereal system as a whole. Details of said complete system are duly set forth in the earlier applications 45 hereinbefore referred to.

Briefly describing the purpose and action 50 of the present invention, it will of course be understood that the person desiring to send a telephonic message speaks into the mouthpiece 12, the sound waves being directed thereby into the megaphone horn 11, wherein by reason of the successive reflections of the sound waves from side to side of the horn or funnel, and the vibration or 55 the molecular action set up in the walls of the megaphone, the sound is amplified or strengthened. While the true cause of such amplification of the sound is more or less uncertain, the fact that it takes place is well 60 established, and is recognized by physicists. From the horn 11 or body of the megaphone, the sound waves pass by the tubes 13 to the diaphragms 17 of the respective micro-telephonic transmitters, and thence by 65 the wires or conductors 22 to the primary

70 coils 26, 27, etc., of the open-core transformers 25. The effects produced in the primary coils through the vibration of the diaphragms of the transmitters set up or induce in the secondary coils thereof the usual concomitant or resultant effects, which are imposed or impressed upon the current flowing through the conductors 39 and 40, and ultimately upon the ethereal waves through or by which the signals are transmitted 75 through space.

By employing a plurality of microphonic transmitters, all communicating with the single mouthpiece and megaphone, I am enabled greatly to intensify or strengthen the 80 effects produced in the electrical conductors, and finally impressed upon the ethereal waves. As a consequence, clear and intelligible transmission of speech results. Seemingly, each separate microphonic transmitter, with its transformer, operates with the same efficiency when grouped and arranged to receive sound waves from a single mouthpiece and megaphone as when but one such microphonic transmitter is used, and 85 there is consequently impressed upon the electric current the aggregate effect of the several microphonic transmitters. The megaphone serves to deliver to each of the transmitters a like series of waves, or in 90 other words, effects an even and perfect distribution thereof to the several transmitters, causing them to act in perfect harmony and with uniform effect.

95 The arrangement of the tubes 13 in relation to the megaphone horn 11 is such that the sound waves are projected into and through said tubes with a minimum of deflection, while the angle of the tubes to the axis of the megaphone is such as to separate 100 the microphonic transmitters only sufficiently to clear one another; and thus to make the plural transmitter compact and 105 symmetrical.

110 The several binding posts 3, 4, etc., are employed for convenience in making the appropriate connections between parts of the apparatus, as usual.

115 While multiple telephone transmitters have heretofore been used to secure a more intense energy of transmission the success of such prior multiple devices has been limited by the reduction in the intensity of action of the sound waves on the individual diaphragms and by possible interference and 120 echoing in the common passage leading from the mouth piece to the transmitters. I have found that by interposing a megaphone between the mouth piece and the group of transmitters and symmetrically 125 arranging the latter I can intensify the effect of the sound waves on each transmitter diaphragm and secure true synchronous action without any disturbing effects of the character mentioned.

While the specific embodiment of my invention here illustrated and described has given very satisfactory results, and is the best form now known to me, it is obvious that the general principles of construction and operation herein set forth may be incorporated in structures of somewhat different form and detail. I therefore do not desire to be restricted to the specific construction or details herein set forth, but contemplate such reasonable variations as would naturally be made by skilled mechanicians and electricians in the practical application and use of my invention.

Having thus described my invention, what I claim is:—

1. A telephonic transmitting apparatus comprising a mouthpiece; a megaphone or horn; a head or block joined to the delivery end of the megaphone, and having a plurality of openings through it in the general direction of the axis of the megaphone; tubes applied to and forming continuations of said openings; and telephonic transmitters carried at the free ends of said tubes, one by each tube, substantially as described.

2. In a telephonic transmitter for ethereal transmission of sounds, the combination of a central head or support bearing a series of substantially identical tubes symmetrically arranged; telephonic transmitters carried one by each of said tubes; and a megaphone applied to the supporting head common to the several tubes, having its larger end

toward the transmitters whereby a sound amplifying chamber is formed.

3. In combination with a bracket or support, a head or block in electrical connection therewith having a series of symmetrically arranged passages or openings; a series of tubes each communicating with one or another of said openings; a series of telephonic transmitters carried by the respective tubes, one by each; a megaphone, the delivery end of which is common to the several tubes, and symmetrically arranged with reference thereto; and a mouthpiece for said megaphone.

4. A telephonic transmitting apparatus comprising a mouthpiece; a megaphone or horn; a head or block joined to the delivery end of the megaphone; a plurality of tubes carried by said head, symmetrically grouped about the axis of the megaphone; and telephonic transmitters carried at the free ends of said tubes, one by each tube, the several transmitters being electrically connected with a common conductor or electric circuit, and thereby adapted to impress upon a current traversing said circuit, their cumulative or aggregate effect.

In testimony whereof I have signed my name to this specification in the presence of two subscribing witnesses.

FREDERICK HOYER MILLENER.
